CLAIM

The ornamental design for a shopping cart, as shown and described.

DESCRIPTION

FIG. 1 is an isometric view of a shopping cart according to an embodiment of the invention, with elements in dashed lines forming no part of the claimed design.

FIG. 2 is a front view of a shopping cart, according to an embodiment of the invention, with elements in dashed lines forming no part of the claimed design and a dashed box identifying a portion of shopping cart illustrated in FIG. 2A. FIG. 2A is an enlarged front view of a portion of the shopping cart shown in the dashed box of FIG. 2, according to an embodiment of the invention, with elements in dashed lines forming no part of the claimed design.

FIG. 3 is a rear view of a shopping cart, according to an embodiment of the invention, with elements in dashed lines forming no part of the claimed design.

FIG. 4 is a right side view of a shopping cart, according to an embodiment of the invention, with elements in dashed lines forming no part of the claimed design.

FIG. 5 is a top view of a shopping cart, according to an embodiment of the invention, with elements in dashed lines forming no part of the claimed design.

FIG. 6 is a bottom view of a shopping cart, according to an embodiment of the invention, with elements in dashed lines forming no part of the claimed design; and,

FIG. 7 is a left side view of a shopping cart, according to an embodiment of the invention, with elements in dashed lines forming no part of the claimed design.
